UNITED STATES PATENT OFFICE.

NORMAN LIPSKY, OF NEW YORK, N. Y., ASSIGNOR TO HALCOLITE COMPANY, INC., A CORPORATION OF NEW YORK.

DESIGN FOR A LIGHTING-FIXTURE WALL BRACKET OR ARTICLE OF SIMILAR NATURE.

Application filed September 18, 1928. Serial No. 28,189. Term of patent 7 years.

To all whom it may concern:

Be it known that I, NORMAN LIPSKY, a citizen of the United States of America, and a resident of the city, county and State of New York, have invented a new, original, and ornamental Design for a Lighting Fixture Wall Bracket or Article of Similar Nature, of which the following is a specification, reference being had to the accompanying drawing, forming a part hereof.

The single figure of the drawing shows a perspective view of the lighting fixture wall bracket or article of similar nature.

I claim:

The ornamental design for a lighting fixture wall bracket or article of similar nature substantially as shown.

NORMAN LIPSKY.
